UNITED STATES PATENT OFFICE.

FRED EMBANKS, OF CLEVELAND, OHIO, ASSIGNOR TO ANASTAZYA KOSZYCZAREK, OF CLEVELAND, OHIO.

COMBINED MUFFLER AND DEODORIZER FOR EXPLOSIVE ENGINES.

1,421,432.

Specification of Letters Patent. Patented July 4, 1922.

Application filed June 16, 1921, Serial No. 478,072. Renewed May 10, 1922. Serial No. 559,924.

To all whom it may concern:

Be it known that I, FRED EMBANKS, a citizen of the United States, residing at Cleveland, in the county of Cuyahoga and State of Ohio, have invented certain new and useful Improvements in a Combined Muffler and Deodorizer for Explosive Engines, of which the following is a specification.

My invention relates to a combined muffler and deodorizer for explosive engines, and the device is particularly constructed for use in automobiles operated by explosive engines, all as substantially shown and described hereafter and more particularly pointed out in the claims.

In the accompanying drawings, Fig. 1 is a reduced side view of an automobile equipped with my engine. Fig. 2 is an enlarged longitudinal section of my device, and Fig. 3 is a cross section on line 3—3 of Fig. 2.

The invention comprises a hollow cylinder 2 having an intake pipe 3 detachably coupled with a screw-threaded pipe 4 extending through the top side of the cylinder near one end thereof. A separate perforated pipe 5 is connected with the lower end of intake pipe extension 4 and pipe 5 is preferably in the form of a coil extending lengthwise of the cylinder within the bottom side thereof. The perforations 6 in coil 5 are graduated in number lengthwise of the coil to provide a freer discharge of the exhaust gases at the outer end thereof than at the opposite end where connected with extension pipe 4, and this coil is submerged in a liquid confined within cylinder 2. Water may be used or water charged with suitable chemicals to deodorize the fumes discharged by the coil. The treated gases escape from cylinder 2 through a T-shaped outlet member 7 which connects with an outlet pipe 8 extending upwardly and rearwardly from the front end of the cylinder, whereas the intake pipe 3 of the device extends forwardly from the rear end of the cylinder toward and to the exhaust manifold of the engine in the automobile.

In this way the intake and outlet pipes for 50 the cylinder extend in opposite directions at the top side of the cylinder so that it is impossible for the liquid to overflow and escape through either pipe 3 or 8 respectively when the vehicle is ascending or descending 55 steep inclines. A horizontal diaphragm 9 is also employed within cylinder 2 to provide separate compartments within the cylinder and to serve as a baffle member to retard and muffle the escaping gases. One end 60 of diaphragm 9 is provided with perforations 10 and the gases can only escape from the rear end of the liquid compartment and must travel forwardly in the upper compartment to reach outlet member 7. A filling plug 11 is provided in the upper side of cylinder 2, and a drain cock 12 is placed at its lower side near the rear end of the cylinder. A removable cap 14 provides a closure for the front end of the cylinder. 70

What I claim is:

1. A combined muffler and deodorizer for explosive engines, having inlet and outlet pipes at opposite ends and extending in opposite directions and crossing to prevent the 75 escape of a liquid in tilting movement of said cylinder and to permit a free discharge of exhaust gases, and said inlet pipe having an outlet extension in the lower portion of the cylinder. 80

2. A combined muffler and deodorizer for explosive engines, comprising a hollow cylinder adapted to contain a liquid having reversely arranged intake and outlet pipe connections at opposite ends thereof and crossing each other above the same. 85

3. A combined muffler and deodorizer for explosive engines comprising a cylinder having a horizontal perforated diaphragm subdividing the cylinder into upper and lower 90 compartments and an intake pipe at one end having a perforated coiled pipe extension located in the lower compartment and an outlet pipe in the other end open to the upper compartment, said lower compartment 95 adapted to contain a liquid to submerge said perforated coiled pipe.

FRED EMBANKS.
